LOOSE LEAF SHIFT BINDER

Walter Easter Haskin, Flushing N. Y., assignor to
Pressed & Welded Steel Products Company, Inc.,
New York, N. Y., a corporation of New York

Application September 4, 1931, Serial No. 561,293

18 Claims. (Cl. 129—9)

This invention relates to a loose leaf binder and particularly to an improved loose leaf shift binder adapted to be made in various sizes and constructed to receive perforated leaves of the full size of the binder, or leaves of less size than the binder, or a combination of different sized leaves.

An object of the invention is to provide an improved loose leaf shift binder wherein one or more leaves may be shifted the distance of one hole or the distance of a plurality of holes.

A further object of the invention is to provide a loose leaf shift binder wherein the leaves, without removal, may be shifted back and forth a distance equal to the distance between one or more holes in the leaves, obviating the necessity of breaking the back of the binder at the longitudinal center line or otherwise so that the back always lays flat throughout the operations.

An additional object, more specifically, is to provide a loose leaf shift binder of the arcuate prong type, the structure being so formed that the prongs may be readily separated laterally and longitudinally by improved mechanical means wherein the element of constant control of the movement of the prongs and the accurate spacing thereof for purposes of shifting or changing the leaves without spilling or tearing of same is of paramount consideration.

In the accompanying drawings—

Figure 1 is a top plan view of a loose leaf shift binder disclosing an embodiment of the invention, part of the back covers being broken away and the inserted leaves being broken away.

Figure 2 is a view similar to Figure 1, but showing the prongs partly open ready for shifting.

Figure 3 is a view similar to Figure 2 but showing the prongs shifted one notch, or the equivalent of the distance between centers of two adjacent perforated holes in the margin of the leaves.

Figure 4 is a view similar to Figure 3, but showing the prongs shifted two notches, or the equivalent of twice the distance between centers of two adjacent perforated holes in the margin of the leaves.

Figure 5 is a view similar to Figure 2 except that the prongs have been moved to a fully opened position ready for the reception or removal of leaves.

Figure 6 is a horizontal sectional view through Figure 8 approximately on line 6—6.

Figure 7 is a sectional view through Figure 2 approximately on line 7—7.

Figure 8 is a transverse sectional view through Figure 2 approximately on line 8—8.

Figure 9 is a transverse sectional view through Figure 2 approximately on line 9—9.

Figure 10 is a top plan view of a cover plate 60 embodying certain features of the invention.

Figure 11 is a perspective view showing a set of prongs embodying certain features of the invention.

Referring to the accompanying drawings by numerals, 1 indicates a back of any desired kind, as for instance a metal channel-shaped member covered with leather or left as a metal piece. This back at the upper edges is provided with hinges 2 and 3 for receiving the back covers 4 and 5. Rivets or bracing members 6 may be used for preventing spreading of the back 1. In the accompanying drawings, two of these rivets are shown, but it will be evident that more or even less than two might be used without departing from the spirit of the invention.

A channel-shaped base 7 is mounted on the back 1, as shown in Figures 7 and 8, the flanges of the base facing downwardly and resting on the bottom of the back. This base is provided with longitudinally positioned slots 8 and 9 through which the actuating pins 10 and 11 project. Rigidly mounted on the base 7 is a cam plate guiding pin 12. A cover plate 13 is formed with depending end flanges 14 and 15 and is mounted on base 7, as shown in Figure 7. This cover plate is also provided with longitudinally positioned slots 16 and 17 identical with and arranged directly opposite slots 8 and 9, so that pins 10 and 11 have exactly the same range of travel as far as these two plates are concerned.

As illustrated particularly in Figures 7 and 8, these pins are connected by a connecting link 18 which is in the nature of a channel iron as shown in Figure 8, with apertured ears 19 and 20 accommodating the respective pins 10 and 11. By reason of this link, both pins must move exactly the same distance at the same time and in the same direction constituting what may be termed a reciprocating slide comprising the said actuating pins 10 and 11 and the connecting link 18.

Arranged between the base 7 and the cover plate 13 are the angle or cam plates 21 and 22. The cam plate 21 is provided with a downwardly extending flange 23 at each end, each of said flanges merging into an inwardly extending cam extension 24. The cam plate 22 is likewise at each end provided with a depending flange 25 merging into the inwardly extending cam extension 26. As shown in Figure 7, the cam plate 22 and its

depending end flanges 25 and inwardly extending cam extensions 26 is positioned in a telescoping arrangement inside the cam plate 21 and its respective depending end flanges 23 and inwardly extending cam extensions 24. As illustrated in Figure 6, the cam plate 21 is provided with a diagonally positioned slot 27 adjacent each end while immediately beneath, the cam plate 22 is provided at each end with diagonally positioned slots 28, slots 28 extending at the opposite angle to slots 27. The respective cam extensions 24 and 26 are each provided with slots 37 and 38, said slots agreeing with the respective slots 27 and 28. The diagonal slots of the respective cam plates and cam extensions are positioned in alignment with the said longitudinal slots 8 and 9 in the base and 16 and 17 in the cover plates so that the actuating pins 10 and 11 are projected through the said longitudinal slots and the said diagonal slots whereby when the actuating pins move back and forth the cam plates 21 and 22 will move laterally toward and from each other. The lateral movement of the respective parallel cam plates by the actuation of the pins 10 and 11 is simultaneous and in opposite directions relative to each other and of equal distance relative to the longitudinal center line of the unit. This arrangement of the cam extensions is to cause the respective cam plates to slide easily and freely back and forth during manipulation of the device. The cam extensions also serve to hold the cam plates rigidly in parallel planes at all times so that the turning of leaves impaled on the respective prongs from side to side can be done smoothly. From Figure 6, it will also be noted that cam plate 21 is provided with an L-shaped slot 29, and a notch 31 together with a substantially T-shaped slot 30 the leg of which is substantially parallel with the diagonal slots 27. Cam plate 22 is likewise provided with an L-shaped slot 32, a notch 33 and a substantially T-shaped slot 34 positioned substantially opposite slot 30, the leg of the T extending in the opposite direction and substantially parallel with the diagonal slots 28. Rigidly mounted between the base 7 and the cover plate 13 is a cam plate guiding pin 12 which projects through the respective T-shaped slots and this arrangement will permit the cam plates to move freely back and forth laterally as desired, but the longitudinal movement thereof to shift the various prongs 35 and 36 is only possible when the guiding pin 12 is opposite the openings or legs of the respective T-slots or in what may be termed the shift position. It will be seen that the guiding pin 12 thus acts to prevent end thrust of the cam plates in the closed and locked positions as shown in Figure 1, and at all other times except the shift positions shown in Figures 2, 3 and 4. As illustrated particularly in Figures 8 and 9, the respective cam plates 21 and 22 are provided with turned-over edges 39 and 40 forming the pinching beads for pinching the connecting sections 41 (for instance Figure 11) of the respective sets of prongs 35 and 36.

The said prongs are thus mounted in a straight line on the respective cam plates. They are preferably arcuate in form, arranged to lie in parallel planes transversely of the back, and grouped in two opposing sets of equal number, the said sets cooperating to receive and impale leaves the margins of which are uniformly perforated at regular intervals. The prongs of each respective set are permanently spaced apart at regular intervals equal to a multiple of the distance between centers of any two consecutive perforations in

the leaves and which may, for example, be equal to four times the said distance. The points or free ends of the said prongs overlap the longitudinal center line of the unit in the fully closed and shift positions shown in Figures 1, 2, 3 and 4, but not in the fully opened position shown in Figure 5, the said points in this instance having been separated sufficiently to create a gap for the reception and removal of leaves. The prongs of one set are staggered with respect to those of the opposing set and arranged to be reciprocated longitudinally of their carrier in the spaces between the latter prongs. In their staggered arrangement and while in their normal or what may be termed non-shift relationship as shown in Figure 1, or in their partly open position as shown in Figure 2, (as contrasted with their single and double shift positions as shown in Figures 3 and 4) each individual prong of one set is positioned in the space between the two immediately opposite consecutive prongs of the other set nearer one of the two than the other and at a point equal to one fourth the distance between them, the said distance being the equivalent of the distance between centers of any two consecutive perforations in the leaves. The respective individual prong members of one set in conjunction with the corresponding individual prong members of the other set form a series of pairs of adjacent overlapping prongs cooperating to form a plurality of arches on which leaves impaled thereon may be turned from one set of prongs to the other. The distance between the two individual prong members forming each of the said arches, while in their non-shift relationship shown in Figures 1 and 2, establishes what may be termed their normal lateral spacing.

Referring to Figure 1 it will be seen that in the normal or non-shift position of the respective sets of prongs, a series of every fourth perforation in the leaves impaled upon the set of prongs 35 coincides and registers with the said set, and, as the said leaves are turned to the opposite set of prongs 36 a second series of every fourth perforation, next adjacent to the first mentioned series, coincides and registers with the said set of prongs 36. By reason of the means for reciprocating the prongs of one set in the spaces between the prongs of the opposing set, the distance or lateral spacing between the two members of each of the said arches may be increased from that of the normal or non-shift relationship. When the respective sets of prongs are moved to the single shift position, as shown in Figure 3, the said lateral spacing is increased to exactly twice that of the normal or non-shift position, or the equivalent of twice the distance between centers of any two consecutive perforations in the leaves whereby when the leaves impaled upon the set of prongs 35 are turned to the opposite set 36 a third series of every fourth perforation in the leaves, next in order to the last above mentioned, coincides and registers with the set of prongs 36. When the respective set of prongs are moved to the double shift position as shown in Figure 4 the said lateral spacing is increased to exactly three times that of normal, or the equivalent of three times the distance between centers of the said perforations whereby a fourth progressive series of the said fourth perforations coincides and registers with the set of prongs 36 when the said leaves are turned from prongs 35. Referring to Figure 5, it will be seen that in the fully opened position of the respective sets of prongs the said lateral spacing between the two members of any of the

said arches is exactly the same as that of normal.

By reason of section 41, the prongs are arranged in couples of two, but by reason of the various apertures in the beads 39 and 40, the individual prongs 35 and 36 are spaced an equal distance apart and are held rigidly in place by reason of the pinching action of the beads 39 and 40. Also, if desired, the respective coupling sections 41 of the prongs may be spot welded or otherwise rigidly held in place. In order to properly and easily manipulate the cam plates longitudinally, a shift lever 42 is provided. This lever is pivotally mounted on the cover plate 13 by a pin 43, which pin may be hollow and if desired may be pressed up as an integral projection from the cover plate. The lever 42 is in effect triangular shaped constituting what may be termed a T-lever and carries pins 44 and 45 which extend through arc-shaped slots 46 and 47 in the cover plate 13 and through the L-shaped slots 29 and 32 of cam plates 21 and 22.

The longitudinal movement of the respective parallel cam plates by the actuation of the lever 42 is simultaneous and in opposite directions relative to each other and of equal distance relative to the transverse center line of the unit.

The U-shaped hand operated member 50 is formed with legs of unequal length swingably mounted or pivoted on the actuating pin 10, as illustrated in Figure 7, and in the performance of its two functions in operating the device it constitutes what may be termed a swingable operating member. By reason of its connection with the reciprocating slide, through the actuating pin 10, it forms a part of a sliding system and acts therein as the pusher or tractor of the said reciprocating slide. The longer leg of the member 50 is provided with a longitudinal slot 49 terminating at one end in an enlargement 51. The T-lever 42 also carries a pin 48 which loosely extends through the slot 49, and by reason of this sliding connection the T-lever 42 and the swingable operating member 50 form a compound lever system whereby when the member 50, acting in this instance as a lever, is swung on its pivot it will actuate the T-lever accordingly. Concerning the enlargement 51 in the slot 49, this is particularly provided in order that the head of pin 48 in the assembly of parts may pass therethrough so that the head will rest on top of the swingable operating member. In addition to this feature, this arrangement permits the swingable operating member to spring over the projection 52, in locking.

For the purpose of actuating the reciprocating slide to move the respective sets of prongs towards or away from each other transversely of the back, the swingable operating member 50 is preferably designed to be advanced or retracted with its longitudinal center line coinciding with the longitudinal center line of the cover plate as shown in Figures 2 and 5. The looped end is prevented from movement to the left of the said center line of the cover plate by reason of the pin 48 of the T-lever projecting through slot 49 and which pin is prevented from movement to the right of the said center line of the cover plate by the lever pins 44 and 45 reaching the limit of their movement in the slots 46 and 47 in the cover plate. The looped end of the swingable operating member is thus confined to movement only to the right of the longitudinal center line of the cover plate, and the range of this latter movement is controlled and limited by what may be termed the shift plate 53, which may be integral

with the said operating member or formed separate and secured thereto. Movement of the looped end of the swingable operating member 50 to the right of the longitudinal center line of the cover plate is for the purpose of actuating the T-lever to lock the parts in their closed position as shown in Figure 1, or to move the prongs to the shift positions as shown in Figures 3 and 4. Plate 53 has an edge 54 positioned parallel to the side edge of the swingable operating member 50, and an inclined edge 54' adapted to move in back of the pin 55 carried by the cover plate 13 when the parts are in their closed and locked position as illustrated in Figure 1. The end surface 54' and pin 55 assist the projection 52 and associated parts in locking the swingable operating member and other parts against accidental movement. The width of the shift plate is such that its edge 54 will freely pass the pin 55 in the operation of opening the prongs as illustrated in Figure 5, and will prevent movement of the looped end of the swingable operating member to the right except at the shift positions illustrated in Figures 2, 3 and 4. The shift plate 53 is provided with a notch 56 merging into an offset notch 57 and acting as a two-step guide when shifting the cam plates. For instance, when it is desired to shift the cam plates, the parts are moved substantially to the position shown in Figure 2, and then the swingable operating member 50 is swung over to the position shown in Figure 3. This will actuate the T-lever to shift the cam plates sufficiently to cause the prongs 35 and 36 to move one step in opposite directions longitudinally of the back or a total combined distance equal to the distance between the centers of any two consecutive perforations 58 and 59 in the leaves 60 and 61. If it should be desired to further shift the prongs so as to shift the same two steps, the swingable operating member 50 is pulled longitudinally from the position shown in Figure 3 and then swung further to the right until it assumes the position shown in Figure 4 whereupon a double shift position has been secured. After the leaves have been properly adjusted, the swingable operating member 50 is swung back to the position shown in Figure 2 and then pushed longitudinally until the parts are in the position shown in Figure 1, after which the swingable operating member is again swung to the right to the locked position and the operation of shifting has been completed.

It is to be especially pointed out that the movement of the respective cam plates and the prongs mounted thereon is always simultaneous and in opposite directions; that they are constantly maintained in their relative lateral and longitudinal positions against accidental movement of one cam plate independently of the other; that the longitudinal movement of the said cam plates can only occur at two fixed, partly open positions at which time the points of the opposing sets of prongs are still overlapped sufficiently to prevent accidental spilling of the leaves in turning the same from side to side and that the points of the respective opposing sets of prongs are maintained rigidly in the same plane by reason of their support by the bearing afforded by the cam extensions 24 and 26 to insure proper registration of the prong points with the perforation in the leaves.

In the operation of the binder, the leaves are placed on the respective prongs 35 starting from the bottom and are overlapped as shown in Figure 1 with the lower name-bearing margin exposed.

The leaves are preferably designed to be of a size to include multiples of four and a minimum of eight marginal perforations equally spaced and the prongs are spaced on centers equal to four times the distance between centers of the said perforations so that each leaf will at all times be held in place by at least two prongs in the case of eight perforations and three prongs in the case of twelve perforations. The opposite set of prongs are equally spaced and the two sets of prongs are offset with relation to each other exactly the distance between centers of the said perforations. The leaves are preferably provided with a marginal space at the lower right hand corner of the face and the upper left-hand corner of the back thereof for the insertion of the name of the account or other index of the record therein contained.

If, for example, the leaves bear the names of accounts arranged in alphabetical order and it is desired to enter a new account in its proper place, all the leaves of the section or page are first turned by hand to register on the opposite set of prongs 36, and the swingable operating member 50 is manually actuated to arrange the parts for a single shift position as shown in Figure 3. All the leaves below the point at which it is desired to insert the new leaf are then swung back to prongs 35 and the swingable operating member 50 returned to the position as shown in Figure 2, whereby a space is provided for the new account. The swingable operating member 50 is then extended to the full open position shown in Figure 5 and the new leaf inserted on prongs 35 in its proper place. Swingable operating member 59 is then restored to its locked position as in Figure 1, and the operation is complete.

If it is desired to remove a leaf and insert a new one in its place, the leaves above the point of change are swung to prongs 36 while the leaf to be removed and all those below it remain on prongs 35. The swingable operating member 50 is then actuated to the full open position, Figure 5, and the change effected.

If it is desired to remove a single leaf and close in the gap, the leaves above the removal point are swung to prongs 36, the balance remaining on prongs 35, and the swingable operating member 50 is actuated to the full open position, Figure 5, and the leaf removed. The swingable operating member 50 is then actuated to the single shift position, Figure 3, and the leaves remaining on prongs 35 are turned to prongs 36. The swingable operating member 50 is then restored to its normal closed position, Figure 1.

If it is then desired to remove two adjacent leaves and close in the gap, the same procedure is followed except that the double shift as shown in Figure 4 is used instead of the single shift.

While I have illustrated what I believe to be the preferred embodiment of my invention, it is obvious that changes may be made in the general form and arrangement of the parts without departing from the spirit of the invention; hence I do not limit myself to the specific details set forth but consider myself at liberty to make such changes and alterations as fairly fall within the scope of the claims.

I claim:

1. A loose leaf binder including a back, a base plate carried by said back, a cover plate carried by said back, a pair of cam plates arranged between the base plate and cover plate, a set of prongs carried by each of said cam plates, said prongs extending transversely of the back, said

cam plates having inclined slots at each end, actuating pins extending through said slots, said base and said cover plate having slots adjacent each end through which said actuating pins extend, said last-mentioned slots extending longitudinally of said back and sliding means for actuating said pins so as to move the pins along said slots whereby said prongs are moved transversely of the back for opening and closing. 80

2. A loose leaf shift binder including a back, a base plate carried by said back, a cover plate carried by said back, said base and cover plates having identical longitudinal slots adjacent each end, a pair of parallel cam plates, each plate having a bent-down end and a cam extension, one plate and its extension telescoping within the other plate and extension, said cam plates and extensions being provided with identically formed inclined slots with the slots in one plate and extension extending at the opposite angle to the slots in the other, a set of prongs carried by each of said plates, actuating pins extending through the slots in the respective cam plates and the said base and cover plates, a link connecting said actuating pins, means for moving said link so that said pins will cause the cams to move said prongs in opposite directions transversely of said back, and swingable means for moving said cam plates in opposite directions longitudinally of said back. 95

3. A loose leaf binder including a back, a base rigidly secured to said back, a cover plate having depending end flanges attached to said base, a pair of prong-carrying cam plates arranged between said base and said cover plate, each of the said cam plates having a pair of inclined slots, 100 said base and said cover plate having longitudinal slots, there being a group of said slots at each end of the binder, an actuating pin extending through each group of slots, a link connecting said actuating pins, and a hand operated member connected to one of said actuating pins for moving said actuating pins whereby said cam plates and the prongs carried thereby may be moved transversely of said back. 105

4. A loose leaf shift binder including a pair of cam plates having transverse slots, each of said plates carrying a group of leaf-receiving prongs, means for moving said groups of prongs toward and from each other, and means for shifting said groups of prongs longitudinally, said latter means including a lever having pins extending into said slots and means for swinging said lever for simultaneously moving said cam plates and said groups of prongs in opposite directions. 120

5. A loose leaf binder including a back, a pair of cam plates, each cam plate having a curled-over edge forming a clamping bead, a plurality of sets of prongs each comprising a pair of prong members and a connecting section, said connecting section fitting within and being rigidly clamped by one of said beads while the prong members extend through the bead, whereby the sets of prongs will move as a unit with the cam plates, means for mounting said cam plates on said back, means for shifting the said plates by cam action transversely of said back for separating said prongs laterally, and means for moving the said plates by lever action for shifting the said prongs longitudinally of said back. 135

6. A loose leaf shift binder including a pair of cam plates, each cam plate having a group of prongs, manually actuated slide means operatively connected with said plates for moving them simultaneously in opposite directions laterally and lever means operatively connected with said 140

145

- plates for moving them simultaneously in opposite directions longitudinally whereby the respective prongs are shifted correspondingly.
7. A loose leaf shift binder including a back, a base plate mounted on said back, a cover plate mounted on said back, a pair of cam plates arranged between said base and cover plates, each cam plate having a transverse slot, a diagonal slot and a group of leaf receiving prongs, a manually actuated swingable operating member provided with a slot extending longitudinally thereof at one end, an actuating pin upon which said swingable operating member is pivoted and which extends through said diagonally positioned slots whereby when said swingable operating member is operated to move said actuating pin longitudinally of the cam plates said cam plates will be moved transversely of the back, a substantially T-shaped lever, a fixed pivot for said lever secured 20 to said cover plate, said pivot being mounted at the junction of the arms of the lever and a substantially equal distance from the end of each transverse arm, means extending from the ends of the said transverse arms of the T-lever into 25 said transverse slots and a shift pin extending through the slot in said swingable operating member, said shift pin being fixed to the third arm of said T-lever whereby when said swingable operating member is swung on said actuating pin, said T-lever will be swung on its pivot and thereby move said cam plates longitudinally of the back for shifting said groups of prongs.
8. A loose leaf binder comprising two opposing groups of co-operating prongs adapted to receive 35 the leaves, reciprocating means for controlling and moving said groups of prongs laterally to an open or a closed position, said shifting of the prongs acting to permit leaves to be inserted or removed, and lever means for shifting and controlling the relative position of said groups of prongs longitudinally while they are in a partly open position, said shifting of the prongs acting to permit leaves to be advanced or retracted along the binder.
- 45 9. A loose leaf shift binder comprising a rigid back, a pair of movable prong carriers mounted on said back, a plurality of prongs mounted on the carriers and adapted to receive leaves, and lever means for shifting said respective prong carriers simultaneously, and in opposite directions longitudinally of said back, whereby said leaves may be advanced or retracted along the binder.
10. A loose leaf shift binder including a rigid back, two groups of leaf-receiving prongs carried by the back, reciprocating mechanical means for moving the said groups of prongs under constant control toward and from each other and transversely of the back, said movement permitting leaves to be added, removed or replaced and lever shifting means for moving said groups of prongs at a partly open position and under constant control relatively longitudinally of the back, whereby groups of said leaves may be 60 turned from side to side to shift them longitudinally of the back relative to other groups of leaves.
11. A loose leaf shift binder including a rigid back, a pair of parallel cam plates carried by said back, a group of arcuate prongs carried by each plate, and a slide mechanism connected with said plates for simultaneously shifting the said plates and the prongs thereon relatively in opposite directions transversely of the back by positive cam action and an accurately controlled 70 lever mechanism connected with said plates for simultaneously shifting the said plates and the prongs thereon relatively in opposite directions longitudinally of the back to positive intermediate and ultimate positions.
12. A loose leaf shift binder including a rigid back, a pair of cam plates mounted on said back, said plates being movable transversely and longitudinally relative to said back, each of said plates provided with a set of leaf-receiving arcuate prongs, a manually operated pivoted member actuating a sliding cam mechanism connected with said plates for shifting said plates transversely of the back, each of said plates having a transverse slot, a lever pivotally mounted centrally on a fixed pivot, means extending from the respective arms of the lever projecting into said slots, said pivoted operating member having a longitudinally positioned slot, a pin extending through said slot and into said lever whereby when said operating member is swung on its pivot it will automatically swing said lever for the longitudinal movement of said cam plates and said prongs carried thereby.
13. A loose leaf shift binder including a pair of cam plates, each plate having a group of leaf-receiving prongs, a sliding system comprising a swingable operating member together with a reciprocating slide connected with the said plates for shifting them by cam action transversely, a compound lever system comprising the said 100 swingable operating member together with a pivotally mounted T-lever connected with the said plates for moving them longitudinally, a shift plate carried by the said swingable operating member provided with a primary and secondary notch, said secondary notch being offset from the primary notch, and a fixed post coacting with said shift plate and adapted to be received in said notches according to the amount of swinging of said operating member whereby the degree of 105 longitudinal shifting of said prongs is governed.
14. A loose leaf shift binder including two cam plates, each cam plate carrying a group of prongs, a manually actuated swingable operating member operatively connected with said cam plates 120 for moving them laterally, and a lever structure formed with means operatively connected with the swingable operating member and the cam plates for moving the latter longitudinally, whereby the respective prongs are moved in like 125 manner.
15. A loose leaf shift binder including a back, two parallel prong carriers mounted on the back, two opposing interspaced sets of identical arcuate prongs lying in parallel planes transversely 130 of the back mounted in a straight line on the respective carriers and adapted to receive leaves perforated at regular intervals, the respective prongs of each of the said sets being spaced apart equally at a distance equal to a multiple of the 135 space between centers of any two consecutive perforations in the leaves, each individual prong of one set being staggered with respect to and positioned in the space between the two immediately opposite consecutive prongs of the other 140 set nearer one of the two than the other, the said individual prong members of one set forming with the respective individual prong members of the opposite set a series of pairs of adjacent overlapping prongs co-operating to create 145 a plurality of arches on which leaves impaled thereon may be turned from one set of prongs to the other, the normal lateral spacing between the two members of each of the said arches being equal to the said distance between centers 150.

of any two consecutive perforations in the leaves, means for sliding the said carriers simultaneously in opposite directions transversely to a partly open position, mechanical means for sliding the said carriers simultaneously in opposite directions longitudinally at the said partly open position whereby the said lateral spacing between the two members of each of the said arches may be increased from that of the said normal by a progressive multiple of the distance between centers of any two consecutive perforations in the leaves.

16. A loose leaf shift binder including a back, a base rigidly secured to said back, a cover plate having depending end flanges attached to said base, a pair of cam plates arranged between said base and said cover plate, each cam plate having a group of leaf-receiving prongs, a transverse slot, a diagonal slot, a substantially T-shaped slot the leg thereof being positioned substantially parallel to the said diagonal slot with the leg of one of the said T-slots extending in the opposite direction to the other, a manually actuated swingable operating member provided with a slot extending longitudinally thereof at one end, an actuating pin upon which said swingable operating member is pivoted and which extends through said diagonally positioned slots whereby when said swingable operating member is operated to move said actuating pin longitudinally of the cam plates said cam plates will be moved transversely of the back, a fixed guiding pin mounted between the said base and cover plates extending through said T-shaped slots whereby the said cam plates will be prevented from longitudinal movement while they are being moved transversely, a substantially T-shaped lever, a fixed pivot for said lever secured to said cover plate, said pivot being mounted at the junction of the arms of the T-lever and a substantially equal distance from the end of each transverse arm, means extending from the ends of the said transverse arms of the T-lever into said transverse slots, and a shift pin extending through the slot in said swingable operating member, said shift pin being fixed to the third arm of said T-lever whereby when said swingable operating member is swung on said actuating pin said T-lever will be swung on its pivot and thereby actuate and control the movement of said cam plates longitudinally for shifting said groups of prongs, the said fixed guiding pin acting to permit the said longitudinal movement of the cam plates only when it is in position to idle in the longitudinal legs of the said T-shaped slots.

17. A loose leaf shift binder including a base

plate having a longitudinal slot, a cover plate mounted on said base plate and having a longitudinal slot identical therewith, a pair of parallel cam plates mounted between the said cover and base plates, each of said cam plates having a substantially L-shaped slot positioned transversely of the plate with a short leg extending longitudinally of the plate, a transverse slot adapted to receive a fixed guiding pin, a diagonal slot adapted to receive a movable actuating pin, and a group of leaf-receiving prongs, an actuating pin extending through the said longitudinal slots of the said base and cover plates and the diagonal slots of the said cam plates, a manually actuated swingable operating member provided with a slot extending longitudinally thereof at one end and pivotally mounted on the said actuating pin whereby when the said swingable operating member moves said actuating pin longitudinally of the cam plates said cam plates will be moved transversely to open and closed positions, a fixed guiding pin mounted between the said base and cover plates extending through said transverse slot whereby said cam plates are prevented from longitudinal movement, a substantially T-shaped lever mounted on a fixed pivot secured to said cover plate, said pivot being positioned at the junction of the arms of the lever, leverage pins extending from the ends of the transverse arms of the lever into said L-shaped slots, and a shift pin extending through the slot in said swingable operating member, said shift pin being fixed to the third arm of said T-lever whereby when said swingable operating member is swung on said actuating pin when the cam plates are in closed positions said T-lever will be swung on its pivot and the said leverage pins will enter the longitudinal leg of the said L-shaped slots whereby the said cam plates and the prongs mounted thereon will be locked against accidental lateral movement, the said fixed guiding pin coacting to prevent longitudinal movement of the said cam plates.

18. A loose leaf shift binder comprising a pair of prong carriers, prongs on each carrier, a manually actuated operating member, reciprocating means connected with said operating member for sliding the respective carriers simultaneously in opposite directions laterally and lever means connected with said operating member for sliding the respective carriers simultaneously in opposite directions longitudinally whereby the respective prongs are shifted accordingly, and a support for the carriers.
